Primary Examiner — Marissa J. Cash

(74) Attorney, Agent, or Firm — DORSEY & WHITNEY LLP

(57) **CLAIM**

The ornamental design for an aviation wheel chock as shown and described.

DESCRIPTION

FIG. 1 is an elevated perspective view of an aviation wheel chock;

FIG. 2 is a reverse, elevated perspective view thereof;

FIG. 3 is a bottom perspective view thereof;

FIG. 4 is a reverse, bottom perspective view thereof;

FIG. 5 is a front view thereof;

FIG. 6 is a rear view thereof;

FIG. 7 is a right side elevation view thereof;

FIG. 8 is a left side elevation view thereof;

FIG. 9 is a top view thereof; and,

FIG. 10 is a bottom view thereof.

The broken lines in the drawings depict portions of the aviation wheel chock that form no part of the claimed design.

1 Claim, 8 Drawing Sheets
